[57] CLAIM

The ornamental design for a nebulizer unit or similar article, as shown.

DESCRIPTION

FIG. 1 is an elevational view of one side of a nebulizer unit or similar article showing our new design;

FIG. 2 is a side elevational view of the right hand side of the article depicted in FIG. 1;

FIG. 3 is a side elevational view of the side opposite from the side depicted in FIG. 1;

FIG. 4 is a side elevational view of the left hand side of the article depicted in FIG. 1;

FIG. 5 is a top plan view thereof;

FIG. 6 is a bottom view thereof; and

FIG. 7 is a cross-section taken on line 7—7 of FIG. 2.

FIG. 1
